US00D983622S

(12) **United States Design Patent** (10) **Patent No.:** **US D983,622 S**
(45) **Date of Patent:** **** Apr. 18, 2023**

(54) **JUICER**

(71) Applicant: **DONGGUAN ZHEN ZHONG KANG PRECISION TRANSMISSION TECHNOLOGY CO., LTD**, Dongguan (CN)

(72) Inventors: **Tangrong Ni**, Dongguan (CN); **Chaojian Lei**, Dongguan (CN)

(73) Assignee: **DONGGUAN ZHEN ZHONG KANG PRECISION TRANSMISSION TECHNOLOGY CO., LTD**, Dongguan (CN)

(**) Term: **15 Years**

(21) Appl. No.: **29/804,326**

(22) Filed: **Aug. 19, 2021**

(30) **Foreign Application Priority Data**

Aug. 2, 2021 (CN) 202130496379.0

(51) **LOC (14) Cl.** **31-00**

(52) **U.S. Cl.**

USPC **D7/665; D7/667**

(57) **CLAIM**

The ornamental design for a juicer, as shown and described.

DESCRIPTION

FIG. 1 is a front perspective view of a juicer showing our new design;

FIG. 2 is a rear perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is an enlarged view of portion 9 of FIG. 1.

The broken lines in the drawings illustrate the portions of the juicer which form no part of the claimed design.

1 Claim, 9 Drawing Sheets
